UNITED STATES PATENT OFFICE.

WALTER SCOTT, OF PLAINFIELD, NEW JERSEY.

DELIVERY MECHANISM FOR PRINTING-PRESSES.

SPECIFICATION forming part of Letters Patent No. 721,840, dated March 3, 1903.

Application filed September 7, 1900. Serial No. 29,256. (No model.)

To all whom it may concern:

Be it known that I, WALTER SCOTT, a citizen of the United States, and a resident of Plainfield, in the county of Union and State 5 of New Jersey, have invented a certain new and useful Improvement in Delivery Mechanism for Printing-Presses, of which the following is a specification.

My present invention has for one object the provision of means for cutting a web (or webs) into sheets and to deliver these sheets with or without collecting cuts; and it consists of certain features of construction, parts, arrangements, and combinations hereinafter 15 described, and more particularly pointed out in the appended claims.

In the drawings hereunto annexed and forming part of this specification, Figure 1 is a diagrammatic side elevation of a printing-machine and folding and delivery mechanism, the frame and other parts being omitted. Fig. 2 is an end view, with frame omitted, of folding and delivery mechanism embodying the present invention. Fig. 3 is a 25 view, partly in section and partly in projection, upon the plane indicated in Fig. 2 by the line X X. Fig. 4 is a view from the left in Fig. 2 and showing certain parts shown in Fig. 2.

The web passes over suitable guides to and 30 between the impression and form cylinders of the printing-couples a b c d and up over a guide cylinder or roller e, thence to and between the impression and plate or form cylinders of printing-couples f g h i, thence 35 about suitable guides to the guide-cylinder k and the V-shaped former V to drawing-rolls l and cutting-cylinders C U. The dotted lines indicate how the web may be led from the couple b to the couple f and also from the couple d to the lower guide-rolls, or the web 40 may be brought in below couple c, which would then be driven in the reverse direction from that in which it is driven when the web comes from above, pass upward through couple c and around the impression-cylinder 45 thereof, and then down to the couple d.

The vertical row of couples a b c d is separated considerably from the vertical row of couples f g h i, thus providing space into 50 which workmen may pass and obtain easy access to all the form and impression cylinders.

The cylinder C has a plurality of cutting

grooves m, (three in the instance shown in the drawings,) and the cylinder U is shown of a size requiring that it have two knives n. The 55 surface of cylinder C is raised adjacent and at each side of grooves m in order to push in the rubber sheaths of knives n during the cutting operation. Behind each groove m is a set of impaling-pins o, which are pivotally connected 60 with arms from shafts p, journaled in cylinder C. The pins o are guided by the cylinder C, as usual. Spring-rods q, of usual construction, connect with arms from shafts p and rotate them until stops r arrest them, 65 thus protruding pins o from cylinder C. Each shaft p has a roller s connected therewith for coaction with certain cams hereinafter mentioned.

t represents cross-heads on shafts u, which 70 are journaled in cylinder C, and v represents rollers journaled on heads t.

w represents double-edged folding-blades carried by shafts u.

x is a circular track for rollers v, and it has 75 a cam y, into which rollers v pass at times or when blades w are to crease the sheets.

z represents brackets by which raceway x is supported from the framework.

The grooves m divide the surface of cylinder C into three sheet-receiving surfaces 1 2 3.

The shaft 4 of cutting-cylinder C has fixed thereto a gear 5, which drives a pinion 6 on an endwise-movable shaft 7, journaled in the framework. Flying cams 8 are fast to the 85 gear 6, which gear is to gear 5 as 2 is to 3. The shaft 7 may be moved endwise to carry cams 8 into and out of the plane in which rollers v move about shaft 4, as by means of a cam 9, fast to shaft 10 of cylinder U, a lever 11, extending from sleeve 12 to and operated by the cam 9, a lever or arm 14 on sleeve 12, and a lever 15, journaled on the same shaft 13 as levers 11 and 14 and connected with lever 14 by a removable screw-bolt 16. The lever 15 90 has an antifriction-bowl thereon which engages with a circumferential groove in the shaft 7. Since cylinder U is two-thirds the size of cylinder C, it results from the above construction that cams 8 are withdrawn from the plane of rollers v every other time a blade w passes cam y, or the cams 8 may be locked in said plane of rollers v by removing bolt 16 from levers 14 15 and inserting it in lug 17

and a threaded hole 18 in the framework, thus causing each blade *w* to be rotated each time it passes cam *y*.

When cams 8 are withdrawn from the plane 5 of rollers *v*, the cam *y* may be filled to convert ring *x* into a complete circle. For this purpose I show an arm 19 on shaft 7, which is angled around outside ring *x* and has a filling-head 20 thereon, which is adapted to 10 enter cam *y* from the side and to supplement and convert ring *x* into a complete circle.

21 is a guide and support for the arm 19, which is loose on, but which moves axially with, shaft 7.

15 22 represents folding rollers or jaws between which the sheets are forced by blades *w*. These rollers are driven in opposite directions, as usual.

23 is a vibratory cam fast on a shaft 24, 20 journaled in the framework, and 25 is an arm fast on said shaft also. The shaft 10 has a cam, as eccentric 26, fast thereon, which cam contacts with a roller 27 on a pivoted arm 28, and arms 25 and 28 are connected by a link 29, 25 pivotally connected with each. A spring-rod 30 presses arm 28 toward cam 26. This construction provides a means whereby cam 23 may be operated to withdraw every other set of pins *o* to cause the release of sheets 30 thereby when cam 9 causes cams 8 to rotate alternate blades *w*.

When cams 8 are set to rotate each blade *w* every time it passes cam *y*, the cam 23 is locked in position such that it will withdraw 35 the sets of pins *o* in their regular order, as by passing a bolt or pin through eye 31 on arm 25 into an opening 32 in the framework.

The pins *o* are wholly or partially withdrawn by a fixed cam 33 as grooves *m* approach their 40 cutting position and are released by said cam 33 in time to impale the new end of the web or webs. When collecting, the sheets on carrier *C* may be prevented from slipping as pins *o* are withdrawn by cam 33 by means of 45 a feed-roller 34, which is journaled in arms 35, which arms in turn are journaled on the shaft of the adjacent roll *l*. A spring-rod 36 (there may be one at each end of roller 34) keeps roller 34 in contact with carrier *C*, and 50 roller 34 is flattened between its ends at 37, so as to avoid the lips at grooves *m*. The roller 34, therefore, has disks at its ends which 55 coact at all times with the cylinder *C*, while the mutilated portion intermediate said disks permits the roller to pass the said lips without striking. Roller 34 is driven from the adjacent drawing-roll *l*, preferably at a slightly-higher surface speed than the carrier *C*, or the roller 34 may be driven from carrier 60 *C*. Guides 38 may be used to prevent sheets from blowing away from pins *o*.

When collecting, the end of the web (or webs) is impaled on a set of pins *o*, and the cylinder *C* is driven in the direction of the 65 arrow thereon in Fig. 2, and shaft 7 and cam 23 are reciprocated in the manner above mentioned. The gear 5 is of a width such that

the gear 6 is always in mesh therewith whatever be the position of the shaft 7 in its end-wise movements, whence the cams 8 are revolved in all positions thereof with respect to the fixed cam. Each set of pins *o* is withdrawn partially or wholly by the cam 33 and is released to impale the new end of the web as or just before the cutting occurs. Alternate blades *w* are rotated, and cam 23 withdraws the pins *o* ahead of said rotated blades, whereby collected sheets are folded off between rollers 22 by the described mechanism. The filler 20 is moved into cam *y*, and cams 8 80 are moved to inoperative position, so that the other alternate blades *w* will not be operated, and at the same times the cam 23 is moved into position such that it does not operate the pins *o* which at those times are passing it. 85

The folded products from rollers 22 may be delivered in any known and suitable manner.

The operation when folding successive cuts is obvious from the foregoing description, it being remembered that bolt-shaft 7 and cam 90 23 have no motion except rotation of the shaft during this operation and that both cams 8 and 23 are in their active or working positions, so that each blade *w* is rotated every time it passes the cam *y*, and each set 95 of pins *o* is withdrawn into the cylinder *C* every time it passes the cam 23. As above noted, the pins *o* may be drawn in partially only as they pass the cam 33, or they may be wholly drawn in. The object of the drawing 100 in the pins at this time is to prevent them from slitting the paper being laid upon the sheet-receiving surfaces of the carrier *C*. On the other hand, by drawing them in so that their sharp points barely protrude from 105 the surface of the carrier or so that their points are within the cylinder *C* the pins make small holes in the paper as they are protruded later. Such later protrusion may take place as or after they reach the line of 110 tangency between the paper and the cylinder. By only partially drawing in the pins when collecting, the sheet already on the carrier is held by the pins while the web of paper coming from the rolls *l* is drawn tautly over the 115 slightly-protruding pin-points, thus aiding in the piercing of the paper, while preventing tearing of large holes.

While I have shown mechanism adapted to 120 collect two sheets or one less than the number of sheet-receiving surfaces on the carrier *C*, I am not to be understood as limiting myself to folding off one or two sheets, for by varying the size of the gears 5 6 and operating the cam 23 correspondingly more than 125 two sheets may be collected and folded off.

Having thus described my invention, what I claim as new, and desire to secure by Letters Patent of the United States, is—

1. The combination with a rotating carrier 130 provided with a plurality of sheet-receiving surfaces, of means for supplying sheets to said surfaces in succession, a series of intermittently-rotating folding-blades, one for

each surface, folding-jaws between which said blades force the sheets, stationary and flying cams for actuating said blades, and means for moving the flying-cam element into and out of its working position or plane, with a cam-filler moved into and out of the stationary cam as the flying-cam element is moved out of and into its working plane or position, substantially as described.

2. The combination with a rotating carrier provided with a plurality of sheet-receiving surfaces, of means for supplying sheets to said surfaces in succession, a series of intermittently-rotating folding-blades, one for each surface, folding-jaws between which said blades force the sheets, stationary and flying cams for actuating said blades, and means for moving the flying-cam element into and out of its working position or plane, said means having disconnectible parts, with devices for retaining said flying-cam element in its working position or plane when said parts are disconnected, with a cam-filler moved into and out of the stationary cam as the flying-cam element is moved out of and into its working plane or position, substantially as described.

3. The combination with a rotating carrier provided with a plurality of sheet-receiving surfaces, of means for supplying sheets to said surfaces in succession, a series of intermittently-rotating folding-blades, one for each surface, folding-jaws between which said blades force the sheets, stationary and flying cams for actuating said blades, and means for moving the flying-cam element into and out of its working position or plane, said means having disconnectible parts, with devices for retaining said flying-cam element in its working position or plane when said parts are disconnected, and means for preventing accidental rotation of said folding-blades as they pass the stationary cam when said flying-cam element is in its non-working position, substantially as described.

4. The combination with a rotating carrier, of means for supplying sheets thereto, an intermittently-rotating folding-blade, stationary and flying cams for rotating said blade, a rotating endwise-movable shaft carrying said flying-cam element, a guided cam-filler sleeved upon said shaft and moving therewith in the endwise motions thereof, substantially as described.

5. The combination of a rotating sheet-carrier, an intermittently-rotating folding-blade thereon, a flying cam, a continuously-rotating cam, a lever connected with the flying cam to move it into and out of working position, a lever actuated by the second-named cam, and means for connecting and disconnecting said levers, substantially as described.

6. The combination of a rotating sheet-carrier, an intermittently-folding blade thereon, a flying cam, a rotating shaft, two cams on said shaft, connections between one of said cams on said shaft and said flying cam for

moving the flying cam into and out of working position, sheet-retainers on said carrier, and connections between the second cam on 70 said shaft and said retainers for causing them to release the sheets as the flying cam operates the folding-blade, substantially as described.

7. The combination of a longitudinally-grooved cutting-cylinder, longitudinal lips at the groove sides, a knife-cylinder having cushions alongside the knife, sheet-retainers, and a pressure-roll having disk ends coating at all times beyond the ends of said lips with 80 said grooved cutting-cylinder and flattened between its ends to avoid striking said lips, substantially as described.

8. The combination with a rotating carrier provided with a plurality of sheet-receiving 85 surfaces, means for supplying sheets to said surfaces, sets of impaling-pins on said carrier, one set for each surface, and means for drawing in said pins before and protruding them as or after they reach the line of tangency of 90 the paper with said carrier, substantially as described.

9. The combination with a rotating carrier, provided with a plurality of sheet-receiving surfaces, of means for supplying sheets to said 95 surfaces, sets of impaling-pins on said carrier, one set for each surface, and means for drawing in said pins before and protruding them as or after they reach the line of tangency of the paper with said carrier, with means for 100 preventing retardation of sheets already laid on said surfaces when said pins are drawn in, substantially as described.

10. The combination of a rotating carrier provided with a plurality of sheet-receiving 105 surfaces, a cutting-groove at the head of each surface, a set of pins behind each of said grooves, a knife-carrying cylinder, and means for drawing in said pins before and protruding them as or after they reach the line of 110 tangency of the paper with said carrier, substantially as described.

11. The combination with a rotating carrier provided with a plurality of sheet-receiving surfaces, a cutting-groove at the head of each 115 surface, a set of impaling-pins behind each of said grooves, a knife-carrying cylinder, and means for drawing in said pins before and protruding them as or after they reach the line of tangency of the paper with said carrier, of means for preventing retardation of 120 sheets already laid on said surfaces when the pins are so drawn in, substantially as described.

12. The combination of two coacting cutting-cylinders, one cylinder thereof having a plurality of sheet-receiving surfaces, and each of said surfaces having a cutting member, a set of sheet-receiving pins for each of said surfaces, a roll coacting with the pin-carrying cylinder to feed the sheets when the pins are drawn inwardly, means for drawing in and protruding said pins to impale the paper being laid upon said surfaces, and devices for 125 130

folding off from said surfaces during non-successive revolutions of said pin-carrying cylinder, substantially as described.

13. The combination of two coacting cutting-cylinders, one cylinder thereof having a plurality of sheet-receiving surfaces, and each of said surfaces having a cutting member, a set of sheet-retaining pins for each of said surfaces, a roll and guides coacting with the pin-carrying cylinder to feed and hold the sheets when the pins are drawn inwardly, means for drawing in and protruding said pins to impale the paper being laid upon said surfaces, and devices for folding off from each of said surfaces during non-successive revolutions of said pin-carrying cylinder, substantially as described.

14. The combination of two coacting cutting-cylinders, one cylinder thereof having a plurality of sheet-receiving surfaces, and each of said surfaces having a cutting member, a set of sheet-retaining pins for each surface, a double-edged folding-blade intermittently rotating, there being one such blade for each of said surfaces, and means for causing each of said blades to fold off during each revolution

tion or during non-successive revolutions of the cylinder carrying it, with means for preventing rotation of said blades as each blade, during non-folding-off revolutions, passes the folding-off point, substantially as described.

15. The combination of two coacting cutting-cylinders, one cylinder thereof having a plurality of sheet-receiving surfaces, and each of said surfaces having a cutting member, a set of sheet-retaining pins for each surface, a double-edged intermittently-rotated folding-blade for each surface, folding-rolls, and means for causing each of said blades to fold off during each revolution or during non-successive revolutions of the cylinder carrying it, with means for preventing rotation of said blades as each blade, during non-folding-off revolutions, passes the folding-off point, substantially as described.

Signed at New York city, in the county of New York and State of New York, this 5th day of September, A. D. 1900.

WALTER SCOTT.
